US00D823890S

(12) United States Design Patent (10) Patent No.: US D823,890 S
(45) Date of Patent: * Jul. 24, 2018

(54) DISPLAY SCREEN OR PORTION THEREOF
WITH ICON

- (71) Applicant: Apple Inc., Cupertino, CA (US)
(72) Inventors: Jonathan P. Ive, San Francisco, CA (US); Christopher Wilson, San Francisco, CA (US); Eric Lance Wilson, San Jose, CA (US)
(73) Assignee: Apple Inc., Cupertino, CA (US)
() Term: 15 Years
(21) Appl. No.: 29/583,599
(22) Filed: Nov. 7, 2016

CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is a front view of a second embodiment thereof. The broken lines in the figures show a display screen or portion thereof, and form no part of the claimed design.
